Henry Williams

UNITED STATES PATENT OFFICE.

JAMES W. DREW, OF BOSTON, MASSACHUSETTS.

CLOTHES-HOOK.

SPECIFICATION forming part of Letters Patent No. 224,003, dated February 3, 1880.

Application filed July 28, 1879.

To all whom it may concern:

Be it known that I, JAMES W. DREW, of Boston, in the county of Suffolk and State of Massachusetts, have invented a new and useful Improvement in Clothes-Hooks, of which the following is a specification, reference being had to the accompanying drawings, in which—

Figure 1 is a perspective view of a clothes-hook embodying my improvement. Fig. 2 is a vertical section of the same. Fig. 3 is a plan.

In hanging clothing, and especially coats, upon the clothes-hooks constructed in the ordinary manner, the hooks injure the clothes by producing a raised place in the garment where it presses down upon the sharp end of the supporting-hook. In order to prevent this injury to coats, coat-hangers are used, the objection to which is, however, that, as they spread from sleeve to sleeve, they occupy too much space.

By means of my improvement a clothes-hanger is produced which occupies no more room than that now in common use, and completely obviates the difficulty above mentioned.

In the drawings, *a* represents the plate which is fastened to the wall, and *b* and *c* the upper and lower supporting-hooks, respectively.

Extending both ways from the outer end of the hook *b* is the cross-piece or supporting-arm *d*, drooping at its ends so as not to injure the shape of the garment hung therefrom.

Openings *d'* may be provided, if desired, so as to lighten the casting. By this means a heavy 35 coat may be hung from the hook without suffering any injury to its shape.

If desired, two hooks may be used to support a heavy overcoat, one near each sleeve or shoulder.

It is obvious that the cross-piece *d* may be applied to either or both the hooks *b c*.

In making my improved clothes-hook the plate *a*, hook *b*, and arm *d* are usually cast in one piece, and the lower hook, *c*, in a separate 45 piece and fitted into the plate *a*, as shown in Fig. 2.

The length and shape of the cross-piece *d* may be somewhat varied, if desired, although the illustration is thought to be about correct 50 in its proportion.

Having thus fully described my improvement, what I claim, and desire to secure by Letters Patent, is—

As an improved article of manufacture, a 55 clothes-hook consisting of the plate *a*, provided, as shown, with one or both the arms *b c*, one or both of which having at their ends the spreading arm or cross-piece *d*, as and for the purpose herein set forth.

JAMES W. DREW.
